(57) CLAIM

The ornamental design for a sports animated antenna, ornament as shown and described.

DESCRIPTION

FIG. 1 is a front right perspective view of a sports animated antenna ornament showing my new design in use with an antenna;

FIG. 2 is a right side view thereof;

FIG. 3 is a front side view thereof;

FIG. 4 is a back side view thereof;

FIG. 5 is a left side view thereof;

FIG. 6 is a top plan view thereof;

FIG. 7 is a bottom plan view thereof; and,

FIG. 8 is a perspective front right view thereof.

The broken lines in the figures depict environment and portions of the ornament that form no part of the claimed design.
